UNITED STATES PATENT OFFICE.

WILLIAM DEPEW, OF PEQUAMING, MICHIGAN.

BOLTLESS RAIL JOINT.

Application filed November 24, 1923. Serial No. 676,801.

To all whom it may concern:

Be it known that I, WILLIAM DEPEW, a citizen of the United States, residing at Pequaming, in the county of Baraga and State of Michigan, have invented certain new and useful Improvements in Boltless Rail Joints, of which the following is a specification, reference being had to the accompanying drawings.

10 This invention relates to railway construction, particularly to rail joints, and has for its object the provision of a novel joint construction including a combined plate and splice bars held together without the use of 15 bolts or other similar securing devices, the parts being so constructed and arranged as to prevent longitudinal creeping of the rails while permitting the inevitable expansion and contraction caused by changes in 20 temperature.

An important and more specific object is the provision of a joint of this character in which the base or plate is equipped with 25 spring catches which will automatically engage the rails when they are dropped into place and which will lock the rails so that upward displacement will be prevented, the distinct feature of advantage being that the rails may be removed for end to end reversal or for any other reason after releasing the spring catches.

An additional object is the provision of a 30 structure of this character which will be simple and inexpensive to manufacture, easy to assemble, rigid in its holding action, efficient and durable in service, and a general improvement in the art.

With the above and other objects and advantages in view, the invention consists in 40 the details of construction to be hereinafter more fully described and claimed, and illustrated in the accompanying drawings in which:

Figure 1 is a side elevation of the assembled joint structure;

Figure 2 is a plan view thereof;

Figure 3 is a cross sectional view on the line 3—3 Figure 1;

Figure 4 is a cross section on the line 4—4 of Figure 1;

Figure 5 is a perspective view showing the end of one rail section;

Figure 6 is a perspective view of the base member; and

Figure 7 is a perspective view of one of the spring catches removed.

Referring more particularly to the drawings, the numeral 10 designates the base of the device which is rectangular in shape and elongated in form so as to extend over two ties A, this plate being provided at its edges with notches 11 at which points spikes B are driven through for the purpose of securing the base to the ties. At its longitudinal edges, this base is thickened to define upstanding side flanges 12 which are preferably beveled downwardly and outwardly.

Rising from the upper surface of the base and formed integrally therewith are bar members 13 which are spaced apart a distance equal to the thickness of the web of a rail of standard pattern. These bar members terminate short of the ends of the base and they are also spaced from the side flanges 12 to define channels 14. Between the bars 13 the base is shown as formed with a longitudinal slot 15 so as to prevent the accumulation of any water or the like which might seep in between the various elements of the joint structure. At their upper edges the bar members are formed near their ends with lugs 16 which are preferably outwardly and downwardly beveled as shown.

The letter C designates the rail sections to be connected and these are of the same cross sectional configuration as the ordinary or standard rail and differ therefrom only in the specific formation of the ends. In actual practice the rails C might be standard rails modified by a comparatively small change though it is naturally preferable that use be made of rails which are initially formed for use in conjunction with the base and splice bar portion of the device. The meeting ends of the rails have their bases cut away at opposite sides of the webs to define slots 17 of a width to receive the individual bar members 13, the webs themselves being received between the bars. The formation of these slots 17 defines tongues 18 which fit between the bars 13 and the adjacent flanges 12.

To prevent longitudinal creeping, the rails are formed on the under sides of their tread portions with recesses 19 which substantially conformingly engage upon the lugs 16 thereof. These recesses should be slightly longer than the lugs to permit expansion and contraction of the rails under the influence of heat and cold.

Instead of using bolts which are com-

monly provided in rail joint structures, I make use of a plurality of spring catches 20 which are suitably anchored within the base 10 and which are accommodated within recesses 21 in the confronting edges of the flanges 12, these catches having shoulders 22 on a line with the upper edges of the flanges.

In assembling the parts, the base 10 is 10 spiked down to the proper place upon the ties A and the rails are simply dropped into place on the base member, the webs entering between the bar members 13 and the tongues 18 entering the channels 14. 15 Ordinarily the catches 20 are in such position that they overhang the channels but as their upper ends are inclined upwardly and outwardly as shown at 23, it is apparent that when the rails are dropped into place 20 the catches will first be forced outwardly by the engagement of the tongues 18 therewith and will then snap into place with the shoulders engaging over the tongues, thereby holding the rails against upward displacement. 25 The lugs 16 are received within the recesses 19 as above described and prevent any longitudinal movement of the rails.

From the foregoing description and a 30 study of the drawings, it will be apparent that I have thus provided a highly efficient and yet inexpensive rail joint which avoids the use of the ordinary fish plates and bolts and which is superior to the ordinary construction in every way particularly in ease of assembling.

While I have shown and described the preferred embodiment of the invention, it is to be understood that I reserve the right 40 to make such changes in the form, construction and arrangement of parts as will not depart from the spirit of the invention or the scope of the subjoined claims.

What I claim is:—

45 1. A rail joint structure comprising a base formed with upstanding flanges at its longitudinal edges, spaced bar members rising from the base in spaced relation to said flanges, rails disposable upon the base between said flanges and having their base portions slotted for the accommodation of said bar members, means for preventing longitudinal creeping of the rails with respect to the base, and means for holding the rails upon the base, said first named means including upstanding lugs formed on the upper edges of the bar members and seating

within corresponding recesses formed in the under sides of the tread portions of the rails.

2. A rail joint structure comprising a base formed with upstanding flanges at its longitudinal edges, spaced bar members rising from the base in spaced relation to said flanges, rails disposable upon the base between said flanges and having their base portions slotted for the accommodation of said bar members, means for preventing longitudinal creeping of the rails with respect to the base, means for holding the rails upon the base, said last named means comprising a plurality of spring catches anchored in the base at said flanges and having overhanging shoulders adapted to engage upon the rail bases. 75

3. A rail joint structure comprising a base formed with upstanding flanges at its longitudinal edges, spaced bar members rising from the base in spaced relation to said flanges, rails disposable upon the base between said flanges and having their base portions slotted for the accommodation of said bar members and means for holding the rails upon the base comprising a plurality of spring catches anchored in the base 80 at said flanges and having overhanging shoulders adapted to engage upon the rail bases, the catch members having their confronting faces inclined upwardly and outwardly from said shoulders to the upper edges whereby to be forced outwardly when the rails are engaged downwardly thereupon, the flange portions of the base being recessed at said catches to permit the outward springing movement. 85

4. A rail joint structure comprising a base formed with upstanding longitudinal flanges, spaced bar members rising from and formed integrally with the base, said bar members being spaced from said flanges to define channels, lugs on the upper edges of the bar members, spring catches anchored in the base and accommodated within recesses in said flanges, the rails having their meeting ends slotted at opposite sides of the webs for the accommodation of said bar members, said slots defining tongues received within said channels and engaged by said catches, the tread portions of the rails being formed on their under sides with recesses receiving said lugs. 100

In testimony whereof I hereunto affix my signature.

WILLIAM DEPEW.
